3,170,752 ELECTRICAL CONNECTOR APPARATUS

Arden D. Van Horssen, Minneapolis, Minn., assignor to
Nu-Line Industries, Inc., Minneapolis, Minn., a corpora-
tion of Minnesota

Filed Oct. 18, 1962, Ser. No. 231,461
3 Claims. (Cl. 339—217)

This invention relates to electrical connectors and more particularly to an improved electrical connector.

It is oftentimes necessary to mount a connector component or contact in an insert which may be rigid or resiliently yieldable. The component must be stable and immovable in the insert and provide a high degree of electrical continuity, but it is also desirable that the component be readily removable from the insert. Although components of this general type have been known in the past, substantially all of such previously known components have been unduly complicated and costly.

With these comments in mind, it is to the elimination of these and other disadvantages to which my invention is concerned.

An object of my invention is to provide a new and improved insertable contact of simple and inexpensive construction and operation.

Another object of my invention is to provide a novel method of producing a socket contact with resilient spring fingers for receiving and positively engaging a pin contact of predetermined maximum size.

These and other objects and advantages of my invention will more fully appear from the following description made in connection with the accompanying drawings wherein like reference characters refer to the same or similar parts throughout the several views and in which:

FIG. 1 is a longitudinal section view through the assembled connector component;

FIG. 2 is a detail transverse section taken approximately at 2—2 in FIG. 1;

FIG. 3 is a detail transverse section view taken approximately at 3—3 in FIG. 1;

FIG. 4 is a detail transverse section view taken approximately at 4—4 in FIG. 1;

FIGS. 5, 6 and 7 show consecutive steps in the formation of the connector component and more specifically:

FIG. 5 is an elevation view partly in section showing a piece of tubing prior to the formation process;

FIG. 6 is a longitudinal section view of the tubing at an intermediate stage of the formation process; and

FIG. 7 is an exploded elevation view, partly in section showing the elements prepared for final assembly.

One form of the invention is shown in the drawings and is described herein.

The electrical connector component is indicated in general by numeral 10 and is primarily adapted for mounting in a rigid or resilient insulating insert 11. The insert 11 has an aperture 12 therein and oppositely facing surfaces 13 and 14 at opposite ends of the aperture and around the periphery thereof. The insert also has an enlarged opening 15 aligned with the aperture 12 and communicating therewith.

The connector component 10 includes an elongate body member 16 which is generally tubular in configuration and which is constructed of a conductive work-hardenable material such as beryllium copper. The body member 16 has a hardened socket contact-defining forward end portion 17 of a reduced diameter as compared to the intermediate portion 18; and the body member also has a tubular rear end portion 19. A plug or quantity of solder 20 or other flowable material is applied to the interior of the tubular rear portion 19 in sealed relation with the inner wall surfaces to define a moisture and hermetic

2

seal between the front and rear portions of the body member.

The forward hardened end portion 17 is provided with a plurality of longitudinally extending linear cuts 21 spaced from each other around the periphery and defining a plurality of elongate resilient spring fingers 22, the outer or forward ends of which are segregated from each other so as to be adapted to converge in a forward direction with respect to each other. The innermost portions of the spring fingers are disposed within, and formed integrally with, the hardened forward portion 17.

The hardened forward end portion 17 has a metallic conductive and rigid shroud 23 thereon in tight-fitting encompassing relation. The rear sleeve portions 24 of the shroud has its rear end spun into an annular recess 25 in the hardened forward portion 17 of the body member 16 to thereby affix the shroud 23 permanently in a predetermined position on the body member 16. The sleeve portion 24 has a forwardly converging conical inner surface 26 disposed along and engaging the innermost end portions of the spring fingers 22 and cause the spring fingers 22 to flex inwardly into convergent relation with each other. It will be noted that the outer ends of the spring fingers 22 are spaced transversely inwardly from the adjacent portion of the sleeve 24 so as to be permitted to flex outwardly under the influence of a mating pin 27, shown in FIG. 1.

The shroud 23 also has an inwardly protruding annular flange or lip 28 disposed forwardly of the outer ends of the spring fingers 22 and with an inner peripheral surface or edge 29 disposed in substantial alignment with the outer ends of the spring fingers so as to limit the size of mating pin allowed access into the socket contact. The outer ends of the spring fingers have outwardly flaring surfaces 30 so as to cam along the front end of the mating pin 27 and cause outward flexing of the fingers 22.

The tubular rear portion 19 of the body member defines a rearwardly facing access opening 31 aligned with the aperture 12 of the insert and normally receiving a shank 32 therethrough. Shank 32 has an enlarged flange 33 defining shoulder surface 34 which engages the surface 13 of the insert 11 and cooperates with the rear end 19 of the body member 16 in cooperative insert-clamping relation so as to hold the shank 32 and body member 16 in predetermined relation with respect to the insert.

A sealing ring 11a encompasses the body member 16 and seals against the insert 11 to prevent moisture migration along the exterior of the component 10 and through the insert.

The shank 32 has an enlarged head 35 at its forward end which defines a rearwardly facing annular shoulder surface 36. Surface 36 normally abuts rearwardly against the forward ends of resilient spring fingers 37 which converge in a forward direction along the shank and are flexible in an outward direction. The spring fingers 37 are mounted on, and formed integrally with, a mounting ring 38 which is captured in and affixedly retained by a permanently deformed or crimped portion 39 of the tubular rear portion 19 of the body member. In the form shown, the portion 39 of the tubular rear end 19 is spun around the configuration of the ring 38 to hold the ring around its entire periphery against any fore-and-aft movement.

It will be noted that the shank 32 has a neck portion 40 which carries a camming slide ring 41 movable forwardly along the shank and engageable with the spring fingers 37 to cam the spring fingers in an outward direction sufficiently as to cause the spring fingers 37 to release the head 35 and permit the shank 32 to be withdrawn from the body member 16 and insert 11. The shank 32 also has an access groove 42 extending longitudinally and linearly along one side of the shank

and through the flange 33 to open rearwardly to the exterior and to open forwardly adjacent the rear edge of camming ring 41. The groove 42 provides access for a tool such as a probe to be inserted inwardly along the groove into engagement with the ring 41 to urge the ring forwardly for camming the spring fingers 37 outwardly and causing the head 35 to be released. 5

The shank 32 also has a wire terminal means 43 on the rear end thereof and in the form shown, comprises a solder pot 44 into which the end of a wire may be 10 inserted and secured by soldering.

With reference now to FIGS. 5, 6 and 7, the novel process or method of forming the body member 18 is described. A length of tube 18' of work-hardenable material such as beryllium copper is used. During the 15 initial stages the tubing 18' is in an annealed condition. During the processing of the tube 18' no heat treating is used. During the formation of the tube 18' it will be seen that in FIG. 6, the tubing has been spun so that the forward portion 17' has a reduced diameter. During the spinning to the reduced diameter, the forward portion 17' is work-hardened. The annular recess 25 is shown completed in FIG. 6. The work-hardened portion 17' forwardly of the annular recess 25 has a cylindrical shape. During the spinning operation, the rear 20 portion 19' is also spun to the configuration shown for receiving a shank therein. The rear end edge 19'a remains in a cylindrical shape allowing subsequent assembly of the mounting ring 38 after the tubing 18' has been formed to the shape shown in FIG. 6. The work-hardened forward end 17' is completed by producing the cuts 21 longitudinally inwardly and linearly along and within the work-hardened forward end portion 17'. The shroud 23 is subsequently applied and the rear 25 edge thereof is spun into the recess 25 as shown in FIG. 1. The spring fingers 37 and mounting ring 38 are subsequently inserted into the rear portion 19' which is subsequently spun inwardly at 39 so as to hold the ring 38 against fore-and-aft movement. 30

It has been found that producing the necessary resiliency in the spring fingers 22 by work-hardening the forward portion is satisfactory and completely comparable to hardening by heat treating. The hardening of the forward portion 17' by working the material and spinning localizes the hardening and allows additional working of the rear end portion 19' of the tube 18' so as to provide for attachment of the conductive shank and spring fingers 37 thereto. 40

It will, of course, be understood that various changes may be made in the form, detail, arrangement and proportions of the parts without departing from the scope of my invention which consists in the matter described herein and set forth in the appended claims. 50

What I claim is:

1. An electrical connector component comprising, 55
  - (a) a body member having a forward end defining an electrical contact means and a tubular rear portion having a rearwardly facing central access opening,
  - (b) a mounting ring fixedly retained within said tubular rear portion adjacent said access opening and having a cylindrical bore extending longitudinally forward from said access opening,
  - (c) said mounting ring being provided with a plurality of forwardly converging and outwardly flexible spring fingers angularly located with respect to each other, 65
  - (d) an elongate shank having means at the rear end thereof adapted for securing a wire thereto and an enlarged head at the forward end adapted for abutting at the rearward portion thereof against the free ends of said fingers in a captured engagement relation,
  - (e) said shank extending forwardly through said access opening and through the bore of said mounting ring, said shank having a first longitudinal portion nearer its rear end of a diameter slightly less 70

than the diameter of said bore and a second longitudinal portion nearer its forward end of a diameter less than that of said first longitudinal portion, the adjacent ends of said longitudinal portions residing said bore with the forward end section of said second longitudinal portion projecting from said bore whereby an annular space is formed between the rear end section of said second longitudinal portion and the forward end section of said mounting ring.

- (f) a cylindrical camming ring normally disposed in said annular space having an outer diameter of a size to fit freely within said bore and an inner diameter of a size to freely encircle said second longitudinal shank portion,
  - (g) said first longitudinal shank portion having a longitudinal groove extending therealong of a depth corresponding substantially to the difference in radii of said longitudinal shank portions, said grooves extending rearwardly through said access opening for admitting a tool for forcefully sliding said cylindrical camming ring forwardly along said second longitudinal shank portion to simultaneously cam said spring fingers outwardly to release the head of said shank and thereby allow withdrawal thereof.
2. An electrical connector component for mounting in an insert having an aperture therethrough comprising,
    - (a) a body member having a forward end defining an electrical contact means and a tubular rear portion with a rearwardly facing central access opening aligned with the aperture of said insert,
    - (b) said tubular rear portion having a generally cylindrical wall with portions thereof adapted to be clamped by said insert,
    - (c) a mounting ring affixed to the inside of said tubular rear portion having a plurality of forwardly extending and outwardly flexible spring fingers,
    - (d) an elongate shank having a rear end with means for securing an electrical wire thereto and a forward portion adapted for extending through the aperture of said insert into said tubular rear portion of the body member,
    - (e) said forward portion of said shank having an enlarged head thereon adapted to abut at the rearward portion thereof against the ends of said spring fingers,
    - (f) said shank having a flange adapted for engaging the rear end of said insert in confronting relation, and
    - (g) a rigid cylindrical camming ring slidably mounted on said shank and engageable with all of said spring fingers at one time whereby said fingers may be simultaneously cammed outwardly to release the head of said shank when said ring is forced forwardly against said fingers,
    - (h) said shank further having an elongate longitudinal access groove with a forward end adjacent said ring and a rearward end exposed to the exterior rearwardly of said flange whereby to permit insertion of a tool for moving said ring forwardly.
3. An electrical connector apparatus comprising,
    - (a) an insulating insert member having an aperture extending therethrough,
    - (b) a conductive body member having portions positioned within said insert member,
    - (c) said body member having a forward end defining electrical contact means and a tubular rear portion having a rearwardly positioned access opening aligned with said aperture of said insert,
    - (d) said tubular rear portion having a rear end clamping against said insert around the aperture thereof in moisture sealing relation,
    - (e) said body member having means interiorly thereof defining a moisture seal to prevent moisture migration from one end of said body member to the other,
    - (f) a plurality of forwardly converging and outwardly flexible spring fingers having rear ends secured with

- in said tubular rear portion and around the periphery thereof,
- (g) an elongate shank extending forwardly through the aperture of said insert and access opening of said tubular rear portion,
- (h) said shank having an enlarged head thereon adapted to abut rearwardly against the ends of said spring fingers and a rear end with wire terminal means thereon,
- (i) said shank also having an outwardly protruding flange confronting and engaging said insert around the aperture thereof, and
- (j) a rigid cylindrical camming ring slidably mounted on said shank and engageable in forward movement with all of said spring fingers at one time whereby to cam and flex said fingers simultaneously in a direction radially outward from said shank whereby to permit said head to pass rearwardly of said fingers,
- (k) said shank further having an elongate access groove with a forward end adjacent said ring and a

5

10

15

20

rearward end extending through said flange whereby to permit insertion of a tool for moving said ring forwardly.
